TENSION CONTROL MECHANISM

Gay M. Bonebrake, Chicago, Ill., assignor to Wm. Wrigley Jr. Company, Chicago, Ill., a corporation of Illinois

Application November 2, 1945, Serial No. 626,321

4 Claims. (Cl. 271—2.3)

1

This invention relates to tension control mechanisms, and more particularly to a mechanism adapted to provide continuous control of the tension of a moving web or the like.

My invention has for a general object the provision of an improved control mechanism for regulating the tension of a moving web or the like by effecting controlled variations of the speed of a web feeding roll at one end of the portion of the web in which tension is to be controlled.

As another object my invention contemplates the provision of a tension control mechanism adapted to use with webs of frangible material or the like and which incorporates a resilient element adapted to soften the controlling action of the mechanism in a manner such that breakage or tearing of the web due to sudden tension variations is avoided.

The present invention has for a further object the provision of a variable speed feed roll drive mechanism and associated apparatus such that the feed roll speed is responsive to the tension of a web or the like which is moved by the feed roll.

It is also an object of my invention to provide a tension control mechanism for regulating the feeding of a web or the like and which is capable of smooth and continuous variations of speed between predetermined maximum and minimum limits and responsive to the size of a loop in the portion of the web in which the tension control is desired.

Other objects and advantages of the invention will be apparent from the following description and the accompanying drawings in which similar characters of reference indicate similar parts throughout the several figures.

Fig. 1 is a fragmentary side elevational and somewhat diagrammatic view of a portion of a machine which incorporates a preferred form of my tension control mechanism;

Fig. 2 is a fragmentary side sectional view with the section taken substantially on a line 2—2 of Fig. 3;

Fig. 3 is a fragmentary top sectional view with the section taken substantially on a line 3—3 of Fig. 1 and wherein certain parts are cut away to illustrate details of construction; and

Fig. 4 is a fragmentary top plan view of a portion of the structure shown in Fig. 3.

Although there are various types of machines which my tension control mechanism is well suited, the exemplary embodiment herein disclosed depicts its adaptation to a machine for laminating a plurality of webs of strip material.

In this adaptation the machine includes a support 10 upon which supply rolls 12, 13 and 14 of strip material may be suitably mounted in a common plane for rotation in response to tension applied to the strip material.

As an example of a practical use, the material in the supply roll 12 may be foil while the materials in the supplies 13 and 14 are paper waxed on both sides and cellophane, respectively. Laminated strip material of this type is well adapted to the wrapping of gum, confections and the like.

Wheels 15, 16 and 17 drawn from the supply rolls 12, 13 and 14, respectively, are laminated and sealed together in closely juxtaposed relationship by passage between closely spaced and substantially parallel rolls 18 and 19, both of which rolls are rotatably supported by the support 10. The roll 18 is carried relative to the support 10 by a coaxial and projecting shaft 20 and desirably is a heater roll heated to a temperature such that it softens the wax on the web 16 to provide a bond between the laminated layers. The heating of the roll 18 may be accomplished by any suitable means, such as the provision of electrical heating elements.

The roll 19 is supported by coaxial projecting end portion 22 which projects through a bearing in the support 10, as shown in Fig. 3. In addition to serving as a backing roll for the heater roll 18, the roll 19 also serves as a driving roll for motivating the webs to draw the material from the respective supply rolls. It is, consequently, desirable that the roll 19 is provided with a surface covering 23 of a material such as cork which is somewhat resilient and has good frictional characteristics for gripping the surface of the web.

After being thus laminated, the combined web 24 extends across portions of the surfaces of idler rolls 25 and 26 and thence between output rolls 27 and 28, at least one of which latter rolls is preferably driven. The idler rolls 25 and 26 serve as guides for the combined web and are carried by suitable shafts 29 and 30, respectively, which project from the support 10. Likewise the rolls 27 and 28 are carried by shafts 32 and 33, respectively, which project outwardly from the support 10.

After passing between the output rolls 27 and 28, the combined web may pass to other parts of a complete machine to be cut for use, or may be rewound as a supply roll of laminated material. The speed of the driven output roll or rolls desirably is substantially constant and correlated to the normal speed of the driven roll 19.

As operation of the machine continues in the process of laminating the separate layers of the combined web, conditions of operation, such as the variations and the sizes of the supply rolls 12, 13 and 14, vary the driving force necessarily applied to the web by the driven roll 19. Thus, to maintain substantially uniform output of the combined web and to prevent tearing or breakage of the web between the driven roll 19 and the driven output rolls 27 and 28, means is provided which is responsive to the tension of the web between those driven rolls to maintain that tension at a practically uniform value by regulating the speed of the driven roll 19.

For driving the driven roll 19, a drive shaft 34 is rotatably supported in coaxial alignment with the supporting end portion 22 of the driven roll 19 by a bearing 35 at one end of a support arm 36. In the disclosed embodiment of my invention, a flanged bracket 37 is secured to the support 10 and carries a projecting stub shaft 38 to which the other end of the support arm 36 is secured by a clamping portion 39, as shown in Fig. 3.

As an exemplary form of driving connection to the drive shaft 34, a pulley 40 is secured to the outer end of the shaft by means such as a set screw 42 and is driven by means such as a belt 43. A collar 44 is secured to the shaft 34 by means such as a set screw 45 on the side of the bearing 35 opposite the pulley 40 to determine the axial position of the shaft 34.

In order that the speed of the driven roll 19 may be varied as the drive shaft 34 is rotated at a practically constant speed, a driving connection between the shaft 34 and the driven roll 19 is provided by variable speed transmission in the form of a planetary mechanism 46. The planetary mechanism 46 includes a sun gear 47 secured to the end of the shaft 34 and a concentrically disposed internal gear 48, between which gears are a plurality of pinions 49 which mesh with the internal and sun gears and are equidistantly spaced circumferentially of those gears.

In order to support the internal gear 48 and provide a partial enclosure for the planetary mechanism, flanged bearings 50 and 52 are secured by fastening means, such as screws 53, to opposite sides of the internal gear. The flanged bearing 50 is rotatably carried by the drive shaft 34 while the flanged bearing 52 is carried by projecting shaft portion 54 on the end of the projecting end portion 22 of the driven roll 19.

A recess 55 is provided in the central portion of the end surface of the flanged bearing 52 to accommodate an annular plate 56 which is drivingly secured to the end of the shaft portion 54. The annular plate 56 rotatably carries the pinions 49 in their circumferentially spaced positions and thus provides a driving connection between the planetary mechanism and the driven roll 19.

It may be readily understood, by consideration of the described structure of the planetary mechanism 46, that when the internal gear 48 is free to rotate, there will be no rotary motion transmitted through the planetary mechanism to the driven roll 19 since the pinions will transmit the rotary motion of the sun gear 47 to the free running internal gear. However, when the motion of the internal gear 48 is impeded to a predetermined extent, the pinions 49 will necessarily travel around the sun gear 47 and thereby transmit rotary motion to the driven roll. The rate of rotation of the driven roll 19 will de-

pend upon the extent to which the motion of the internal gear is impeded and will be maximum when the internal gear is locked.

To accomplish the desired result of controlling the tension in the web in the present instance, the ratios of the gears of the planetary mechanism are preferably so related to the diameter of the driven roll 19 that when the internal gear is locked, the web will be driven at a rate materially in excess of the rate of motion imparted to the web by the driven rolls 27 and 28. Under these circumstances, normal tension will be maintained in the combined web 24 between the driven roll 19 and the driven rolls 27 and 28 when there is some rotary motion of the internal gear 48.

In order to effect the desired control of the operation of the planetary mechanism 46 in response to the tension of the combined web 24, I have provided a frictional control mechanism which includes a brake band 57 adapted to contact with a brake drum 58 which is secured to the outer surface of the internal gear 48. One end of the brake band 57 is adjustably secured to a bracket 59 on the support 10 by a clamp 60 having thereon a screw 62 which is threaded into a nut 63, said nut being rotatably secured to the bracket 59. The other end of the brake band 57 is secured to one end of a lever 64 by means such as a clamp 65.

As illustrated in Figs. 2 and 3, the lever 64 is rotatably supported on the projecting shaft 38 between one side of the bracket 37 and a locating collar 66 which is secured to the shaft. The other end of the lever 64 is movably connected through a motion transmitting linkage 67 to a brake control arm 68, which brake control arm is supported at one end for swinging movement by a shaft 69 projecting from the support 10.

In the disclosed embodiment the linkage 67 includes an adjustable element comprising a rod 70 having its ends threaded into connectors 72 and 73, which connectors are rotatably connected to the end of an angularly projecting arm 74 of a support bracket 75 and to the end of the lever 64 opposite the brake band, respectively. A spring 76 having one end anchored to the support 10 and its other end secured to a projecting arm 77 on the bracket 75 biases the brake mechanism to a position such that the brake band is released from the drum.

Downward swinging movement of the arm 68 in a clockwise direction, as viewed in Fig. 1, actuates the linkage 67 and lever 64 to tighten the brake band about the drum 58 so that frictional engagement is affected to control the rate of movement of the internal gear and thus to control the rate of rotation of the driven roll 19.

In order to utilize this controlling action of the variable speed transmission to effect control of the tension of the web between the driven roll 19 and the driven rolls 27 and 28, the arm 68 has a bracket 78 secured to its swinging end for rotatably supporting a movable roll 79.

Desirably, the normal position of the roll 79 is displaced to one side of the idler rolls 25 and 26 so that in passing between the idler rolls and over the movable roll, a variable loop is formed in the combined web 24. The biasing force of the spring 76 acts in opposition to the tension of the web against the roll 79 to determine the position of that roll and thereby to determine the operation of the planetary mechanism 46.

The provision of a sizable loop in the com-

bined web 24 between idler rolls 25 and 26 where the web passes over the movable roll 19 establishes a variable section in the course of the web and prevents variations in tension from causing slippage or tearing the web.

As an additional factor promoting smooth operation of the control mechanism and easing the variations of the control mechanism in response to sudden variations of web tension, I preferably make the arm 68 of resilient material having characteristics such that it will flex in response to variations of web tension and thereby help to absorb shock or sudden changes but will not flex to an extent that would defeat the responsive operation of the brake mechanism. It is to be understood that the arm 68 may be rigid but when resiliently flexible, as preferred, it is sufficiently rigid to transmit the desired controlling forces against the biasing force of the spring 76 and to apply braking force to the brake band 57.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a tension control mechanism for regulating the tension of a flexible web or the like in a machine including support means rotatably carrying thereon driven rolls in separated relationship and a pair of idler rolls between the driven rolls over which rolls the web passes, the combination comprising a planetary mechanism for driving one of said driven rolls, said planetary mechanism including concentrically disposed internal and sun gears and a plurality of intermediate pinions meshing with the internal and sun gears, driving means connected to the sun gear, a plate connected to the last mentioned roll and rotatably carrying said pinions, a brake drum secured to the internal gear, a brake band surrounding a portion of said brake drum, means adjustably anchoring one end of the brake band, a rotatably supported lever having the other end of the brake band secured to one end thereof, a flexible arm supported for swinging movement toward and from said pair of idler rolls and having an idler roll rotatably mounted thereon at a position normally at one side of the pair of idler rolls so as normally to effect the formation of a loop in the web passing around the last mentioned idler roll intermediate said pair of idler rolls, said flexible arm being connected to the other end of said lever, means biasing said flexible arm in a direction away from said pair of idler rolls and such that the brake band is separated from the drum, whereby increased tension in the web moves the flexible arm against the force of said biasing means and tightens said brake band against the drum.

2. In a tension control mechanism for regulating the tension of a flexible web or the like in a machine including support means rotatably carrying thereon driven and idler rolls in separated relationship for guiding and moving the web, the combination comprising a planetary mechanism providing a variable speed driving element for one of said driven rolls, said planetary mechanism including concentric gears and a plurality of intermediate pinions meshing with the concentric gears, driving means connected to one of

the concentric gears, means for drivingly connecting said pinions to said one of the driven rolls, frictional means operatively connected to the other of said concentric gears for controlling the rate of rotation thereof relative to said one of the concentric gears and thereby regulating the rate of rotary motion of said pinions and said one of the driven rolls, and web deflected means responsive to the tension of said web between two of the first mentioned rolls for controlling the frictional means, the last mentioned means including an elongated arm supported at one end thereof for swinging movement and carrying a roll at its free end over which the web extends, and said arm being flexible such that it yields between its ends in response to changes of web tension and thereby tends to limit the suddenness of web tension variations.

3. In a machine in which a web of flexible material is fed from a rolled supply across a series of rolls in spaced relationship and including a driven input roll near the supply, an output roll and intervening guide rolls, a tension control mechanism for regulating the web tension between the driven input and output rolls and comprising in combination, a variable speed transmission through which the input roll is driven, said transmission including a planetary mechanism having coacting driving, driven and controlling elements, said driven element being connected to the last mentioned input roll, frictional means coacting with said controlling element to vary the speed of the driven element while the driving element moves at substantially constant speed, said frictional means including a bodily movable leverage including an operating member carrying a roll which engages the web intermediate the input and output rolls and to be deflected by the web in response to changes in tension thereof, and said roll carrying member being relatively flexible for movement of the roll in response to slight variations of web tension without bodily movement of the leverage.

4. In a tension control mechanism for regulating the tension of a flexible web during movement of the web in one direction in a machine including support means rotatably carrying thereon first and second driven rolls in separated relationship and in sequence corresponding to the direction of web movement and a pair of idler rolls between the driven rolls over which idler rolls the web passes, the combination comprising a planetary mechanism for driving the first driven roll, said planetary mechanism including concentrically disposed internal and sun gears and a plurality of intermediate pinions meshing with the internal and sun gears, driving means connected to the sun gear, a plate connected to the said first driven roll and rotatably carrying said pinions, a brake drum on an outer surface of the internal gear, a brake band surrounding a portion of the brake drum, means for adjustably anchoring one end of the brake band, a rotatably supported lever having the other end of the brake band secured to one end thereof, a flexible arm supported at one end thereof for swinging movement toward and from said pair of idler rolls and having an idler roll rotatably mounted thereon at a position normally at one side of the pair of idler rolls so as normally to effect the formation of a loop in the web passing around the last mentioned idler roll intermediate said pair of idler rolls, said flexible arm being connected to the other end of said lever, means for biasing said flexible arm in a direction away

7
from said pair of idler rolls and such that the
brake band is retracted from the drum, whereby
increased tension in the web moves the flexible
arm against the force of said biasing means and
tightens said brake band against the drum to in-
crease the speed of said first driven roll.
